OTHER PUBLICATIONS

U.S. Appl. No. 14/856,309, filed Sep. 26, 2015, Yang et al.
(Continued)*Primary Examiner* — Cynthia Ramirez(74) *Attorney, Agent, or Firm* — Knobbe, Martens, Olson & Bear, LLP(57) **CLAIM**

The ornamental design for a trash can, as shown and described.

DESCRIPTION

FIG. 1 is a top, front, left-side perspective view of a trash can of our design;

FIG. 2 is a top, rear, left-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The broken lines shown in the figures are included for the purpose of illustrating portions of the trash can and form no part of the claimed design.
